UNITED STATES PATENT OFFICE.

EMILIE MERLE AND APOLLONIE MERLE, OF PARIS, FRANCE.

ADJUSTABLE MODEL OR DUMMY FOR DRESS-MAKERS' USE.

SPECIFICATION forming part of Letters Patent No. 317,830, dated May 12, 1885.

Application filed May 31, 1884. (No model.) Patented in France December 5, 1882, No. 152,453, and in England November 12, 1883, No. 5,346.

To all whom it may concern:

Be it known that we, EMILIE MERLE and APOLLONIE MERLE, citizens of France, residing at Paris, in the Department of the Seine, 5 have invented new and useful Improvements in an Adjustable Model or Dummy for Dress-Makers' Use, and for other purposes, (for which French Letters Patent No. 152,453, dated December 5, 1882, have been obtained,) of which 10 the following is a specification.

This invention has for its object to make a model or dummy which may be adjusted to conform to the figures of different persons. By making the model adjustable the necessity 15 for a large number of them and the consequent expense and trouble of obtaining and keeping them are avoided.

The invention consists in the adjustable model or dummy and combinations and arrangements of its parts, as hereinafter explained.

The accompanying drawings represent two forms of model or dummy constructed in accordance with the invention, one form being 25 shown in Figures 1 to 5, and another in Fig. 6. Fig. 1 is a sectional elevation looking to the rear; Fig. 2, a front elevation; Fig. 3, a profile or side view; Figs. 4 and 5, views in horizontal section looking upward, and Fig. 6, a perspective. Figs. 1 and 4 show the figure contracted; Figs. 2, 3, and 5, expanded. Fig. 6 represents a model embodying the invention in its more complete form. Fig. 7 is a partial 30 view in central vertical section.

Referring to Fig. 1, the threaded rod A, by 35 which the principal adjustments are effected, passes freely through the bearing a, soldered in the upper end of the iron tube C, which supports the figure.

The rod A has a left-hand thread, a", at the lower part, and a right-hand thread, a', of greater pitch above it. The thread a' engages 40 a nut, H, the thread a" a nut, H', both of which nuts slide on the tube C, and are guided 45 by slots therein.

The upper nut, H, is connected by links I I' with the bust-sections E E' E" at the front of the figure. The ends of the links are jointed to the eye-plates J J' J", Figs. 4 and 5, on 50 the respective sections.

The lower nut, H', is connected by links K

K' with the back-sections F F'. The bust-sections are separated from each other by vertical division-lines. Each of the bust-sections E E' E" F F' is hinged by means of flexible 55 metal strips e, or by other suitable means, to the wooden collar or ring G, that surrounds the tube C. A leather band, g, surrounds the metal strips. The front and back sections are connected with each other at the shoulders by 60 small hinges e'. (See Fig. 3.)

By turning the rod A in one direction (to the left, as shown) the nuts H H' will be drawn together, and the links I I' I" K K', being drawn toward a horizontal position, spread 65 apart and push outward the lower ends of the bust-sections until the extreme position is reached. Since the pitch of thread a' is greater than that of lower thread, a", the front sections will be separated more rapidly than the 70 back ones. Thus the proportion of the figure will be preserved, notwithstanding the adjustment. In Fig. 6 the means of adjustment also effect this "differential adjustment," as it may be called. The rod A has only one thread, 75 which engages a nut in the collar of the figure, and the said rod is connected at its lower end with a plug that slides in the interior of the tube C, and is connected by ears h with the five-armed slide d'. Above this is a second 80 slide, d, which moves freely on the tube C. The slide d is a ring with five small lugs on the circumference, each above one of the arms of the slide d'. The two slides are connected by inclined rods, l, each of which passes through an 85 eye, 2, on the inside of one of the bust sections. The rods l are fastened to the two slides d d'. When the screw-rod A is turned to raise the two slides d d', the inclined rod slips in the eyes 2 and 90 press out the bust-sections. When the screw-rod A is turned in the opposite direction the bust is contracted. The relative movement of each bust-section depends upon the relative 95 inclination of the corresponding rods. As the slides d d' and inclined rods l are rigidly connected, the form of the bust after the parts have once been arranged properly is maintained through all the adjustments.

In order to bridge the space between the bust-sections at the bottom, a system of crossed 100 and jointed metal rods L', Fig. 2, or G", Fig. 6, (similar to lazy-tongs,) is at the ends fastened

to the side sections E E' and at the middle to the section E''. The system G'', Fig. 6, extends only a short distance beyond the edge of the bust-sections E E', but the system L' extends 5 farther, as clearly represented in Fig. 2. The joints allow the system of rods to expand and contract according to the adjustment. In order to further protect the spaces between the sections, elastic lacing p' may be laced 10 across one or more or all of them between the lace-hooks P', as shown in Fig. 2.

Attached to the bust-sections at their lower edges, or to the rods L' or G'' at their crossings, are a number of longitudinal wires or 15 strips, P, which constitute the lower part of the model or dummy. These wires are confined at the waist Q, Fig. 6, by the girdle R of leather, or preferably of steel, which can be adjusted, as required, by an ordinary buckle 20 or other means, and which is graduated, say, to centimeters. (See Fig. 6.) It may be adjusted vertically on the wires P or on other supports depending from the bust-sections. The elasticity of the wires or strips P allows 25 the girdle to be taken in or let out at will. In Fig. 1 the wires P are simply confined at the bottom by the hoops N N' N''; but in Fig. 6 they are combined with means for adjustment.

30 At the hips S are a series of small slides, u, each connected by a link, T, with the ring K*, which can be raised and lowered by a nut, M, on the screw H''. The screw is tapped through the sleeve at the apex of the tripod, which 35 supports the dummy figure and extends into the tube C. The nut with which the ring K* is connected slides freely in the tube C, and when the screw H'' is turned said nut is moved up or down in the tube C, and, of 40 course, moves with it the ring K*. The tube C rests upon the nut o, which is prevented from turning with the screw H'' by the friction of the tube against it, or by holding by hand, if necessary. By moving the nut up 45 and down, the links T are thrown out or drawn in, and this movement increases or diminishes the circumference of the hips.

A second and lower ring, L, is attached to the former by means of one or more connections, l, which may be metal bars fastened at the lower end to the ring L and at the upper 50 end to the ring K*. These connections are graduated in divisions corresponding to the variable circumference of the hips in order to 55 give a sure indication in adjusting by the upright screws b. Preferably two of these screws are used. The other screw would be precisely like it, but arranged on the opposite side of the tube. Each screw b turns freely 60 in a lug inside the ring L, and is tapped through a lug on the inside of the ring M. It has a head, b*, for turning it. When turned in one direction it draws down the ring M, when turned in the other it raises it. To the 65 ring L slides u' are connected by the inclined links T', and these are connected at the middle by the links a*, clinched in the opposite direc-

tion with the intermediate ring, M. This ring M is independent of the central tube, and is maintained by the adjusting-screws b the proper distance from the ring L connected with the upper ring, K*, by the two connections l. By turning these screws the intermediate ring is raised or lowered parallel to itself, or if only one screw be turned it is inclined to its former 70 plane, and thus gives to the links a* T' and slides u' a movement of opening and closing which increases or diminishes the section through the lower slides without altering the section through the upper slides. The upper 80 and lower slides, u u', are maintained equal distances apart by the vertical rods q*, which prevent the wires or strips P bending between them. At the upper part of the vertical rods at B, is a rubber ring, (not shown,) which surrounds the rods q* and wires P, and prevents them spreading out.

On the upper and lower rings, K* L, are the lugs c. There are two pairs of lugs on each ring. A screw, m, (which can be turned 90 by a key,) is journaled in each pair of lugs, and is tapped through the ends of the rods p, which are fastened to the nuts M'' L'' respectively. The nut L'', as well as the nut M'', engages the screw H'', and slides in the tube C. 95 The screws m, it may be observed, support the rings K* L. By turning them the rings can be moved in a horizontal plane toward the front or rear, so as to make the model or dummy conform to the different vertical lines of 100 the figure to be imitated.

By the combination of these different movements controlled by the screws A H'' and the screws b in the exterior form of the model or dummy can be changed in any desired way. 105 Its height is adjustable by means of the nut o on the screw H''.

In Fig. 1 there is a nut, O', on the screw H'' for raising and lowering the dummy or model. The screw H'' is fixed in the bottom 110 of the tube C, and slides in the tripod D. A set-screw, q, is provided for retaining it in whatever position it may be adjusted. In Fig. 6 the legs of the tripod turn on the hinges s whenever the three screws which maintain 115 them in the position shown are raised, and the model or dummy can be packed away in small space.

The ends of the wires or strips P in Fig. 6 are connected by the jointed rods V.

The operation of the device is as follows: Referring to Fig. 1, the height of the dummy from the floor is adjusted by turning the nut O'. The bust-sections are then spread apart or drawn together by turning the rod A. The girdle R, Fig. 2, is also expanded or drawn in to the proper extent. Thus the shape of the bust is changed as may be required. Referring to Fig. 6, the height of the dummy from the floor is regulated by turning the nut o. The bust-sections are spread apart or drawn together by turning the screw-rod A. The girdle R is let in or let out. The longitudinal wires or strips P are adjusted by turning by

hand the screw H", so as to raise or lower the rings K* L.

It is evident that modifications in details can be made without departing from the spirit of 5 the invention. The number of bust-sections may be varied. Parts of the invention may also be used separately.

The invention is applicable to all kinds of figures, those of men and children, for example, as well as of women.

Having now fully described our said invention, and the manner of carrying the same into effect, what we claim is—

1. The combination, with the bust-sections, 15 of the adjusting mechanism common to and connected with both the front and the back sections, so as to adjust them simultaneously, and comprising devices, such as the screw rod, nut, or nuts, and connections, substantially as described, the said devices being constructed and arranged as explained, whereby the front sections are movable faster than the back ones to retain the form notwithstanding the adjustment, as set forth.

25 2. The combination, with the adjustable bust-sections, of the extensible and collapsible system of crossed and jointed rods connecting the same at the bottom, substantially as described.

30 3. The combination, with the adjustable bust-sections, and adjusting mechanism for spreading apart and drawing together the said sections, of the elastic lacing across the spaces between the sections, substantially as described.

35 4. The combination, with the adjustable bust-sections, of the series of longitudinal

wires or strips fastened to the said bust-sections at the lower edge thereof, said wires being separate pieces from the bust-sections and 40 several of them depending from each of said sections, substantially as described.

5. The combination, with the adjustable bust-sections, of the extensible and collapsible system of crossed and jointed rods, and the 45 longitudinal strips or wires fastened to the said rods or to them and the bust-sections, substantially as described.

6. The combination, with the adjustable bust-sections, separated from each other by 50 vertical division-lines, and the longitudinal skirt-wires depending therefrom, several of them being attached at the lower edge of each bust-section, of the adjustable girdle confining the wires at the waist of the figure, the main 55 portions of said figure being below the girdle and forming a skirt, substantially as described.

7. The combination, with the adjustable bust-sections, separated from each other by vertical division-lines, and the longitudinal 60 skirt-wires depending therefrom, several of them being attached at the lower edge of each bust-section, of the girdle, confining the wires at the waist, and the stretchers connected with said wires below the girdle for adjusting the 65 skirt of the figure, substantially as described.

In testimony whereof we have hereunto set our hands in the presence of two subscribing witnesses.

EMILIE MERLE.
APOLLONIE MERLE.
